UNITED STATES PATENT OFFICE

MARC RESEK, OF CLEVELAND HEIGHTS, OHIO, ASSIGNOR TO PERFECTION STOVE COMPANY, OF CLEVELAND, OHIO, A CORPORATION OF OHIO

LIGHTING DEVICE FOR RETORT STOVES

Application filed February 7, 1927. Serial No. 166,304.

This invention pertains to a lighting device or starting burner for liquid fuel stoves of the retort class, the same, though not so limited, being especially designed for use with stoves of the type shown in applications Serial Nos. 126,366 and 149,353, filed jointly by Lee S. Chadwick and myself on August 2, 1926, and November 19, 1926, respectively.

Among the objects of the invention are the production of a device of the above mentioned character that is very efficient; that is safe and reliable; that is simple and easy of operation; that is quickly responsive to the application of a lighted match or other igniter; that burns quietly with a clean, blue flame, avoiding the roaring noise common to prevailing burners of this class; that is relatively simple of construction and economical of manufacture; that is compact; and that is not liable to get out of order nor become clogged with sediment, scale or carbon, or with boiled over foodstuff, though capable of being easily opened or disassembled for the purpose of cleaning should such become necessary.

Other objects will appear as I proceed to describe the invention with reference to the accompanying drawings wherein like parts are designated by corresponding numerals throughout the several views.

In the drawings Fig. 1 is a fragmentary sectional front elevation of a stove incorporating my improved lighting or starting burner; Fig. 2 is a plan view of the same with parts broken away to reveal certain connections; Fig. 3 is an enlarged fragmentary transverse section through the stove on the line 3—3 of Fig. 1; Fig. 4 is a plan view of the parts shown in Fig. 3; Fig. 5 is a section through the lighting or starting burner and certain of the stove parts associated therewith, the plane of such being indicated by the line 5—5 of Fig. 3; Fig. 6 is an enlarged sectional detail of the valve and generator of the lighting or starting burner; Fig. 7 is an enlarged sectional detail of the portion of the fuel conduit to which the tube is connected that leads to the lighting or starting burner, the section being taken on the line 7—7 of Fig. 1; and Fig. 8 is a section on the line 8—8 of Fig. 7.

The stove structure comprises a top 1, legs 2 that support the top a suitable distance above the floor, end panels 3 and 4 that extend from the front to the rear legs at the opposite ends of the stove, and a burner pan 5 that is supported between the end panels a suitable distance below and parallel with the top.

A manifold 6 is supported within the space between the top 1 and the burner pan 5 by brackets 7 that are carried by and extend inwardly from the end panels 3 and 4 and have their inner ends suitably secured to the ends of the manifold. Burners 10 and 11 surround the opposite ends of the manifold 6 and are located beneath openings 12 in the stove top. Rising from about the longitudinal center of, and preferably formed integral with, the manifold 6 is a mixer 15 whose outer end is turned toward the burner 10, and the same is formed with an end wall 16 which shields the downwardly directed inlet end of the mixer from the direct heat of the burner flame.

Secured to the outer side of the end panel 4 in about the plane of the burner pan 5 is a unit 18 that is in the form of a substantial casting and to which is adapted to be removably attached a fuel reservoir 19. Rising from the inner end of the conduit 18 is a fuel pipe or conduit 20 that includes a valve 21 and connects at its upper end with a tubular retort 22 that is projected through an aperture in the end panel 4 and across the burner 10 and has its inner end projected through a hole in the end wall 16 of a mixer 15. This retort is detailed in an application filed jointly by Lee S. Chadwick and myself on December 6, 1926, Serial No. 152,798. The valve at the inner end of the retort is controlled by a hand wheel 23 that is applied to the outer end of the valve stem 24.

In the type of stove herein shown, the fuel is fed by air pressure from the reservoir 19, through the fuel conduit 20—when the valve 21 is open—to the retort 22 where, under normal operating conditions, it is vaporized by the heat from the burner 10. With the valve of the retort open, the vapor issues from the retort into the mixer 15 where it mixes with air entering through the downturned end of

the mixer and passes on therewith to the manifold 6 through which it is distributed to the burners 10 and 11, passage of gas to the latter burner being controlled by a valve whose operating handle is shown at 25.

It may be explained that air is supplied to the reservoir 19 by means of a suitable pump. This is in accordance with common practice and therefore illustration is deemed unnecessary. So far as the present invention is concerned, the fuel system might be of the gravity feed type.

My improved lighting device or starting burner is designated generally by the numeral 30 and is located adjacent the end wall 16 of the mixer 15 directly beneath the adjoining end of the retort 22. The burner is preferably composed of two mating sections 31 and 32, which may be cast, the section 32 being substantially a counterpart of the portion of the section 31 against which it is engaged. The section 32 is secured to the section 31 by a screw 33, and it is properly positioned with respect to the section 31 by said screw and a dowel pin 34 that extends through registering holes in the two sections and enters an aperture in the end wall 16 of the mixer. Slots 35 are sawed, milled, or otherwise formed in a substantially horizontal portion 36 of the burner body directly beneath the retort 22, and the adjacent end wall of the section 31 is cut away to provide a narrow vertical slot 37 when the two sections are fitted together. A deflector 38 is disposed opposite the slot 37 and the same is preferably formed integral with the sections 31 and 32.

The burner body encloses a mixing chamber 40 including a goose neck portion 41 that joins, through a passage 42, an air inlet 43. This inlet is shielded from the flame of the burner by an upwardly and rearwardly directed wall 44, and a bead 43^a that extends across the lower side of the air inlet 43 prevents any boiled over food or other foreign matter that drops upon the burner from entering said inlet.

A bracket 45 extends forwardly from and is preferably formed integral with the section 31, and near the previously mentioned deflector 38 has an aperture through which a screw 46 is engaged which serves to secure the burner to the end wall 16 of the mixing chamber 15. The above mentioned dowel pin 34 assists the screw 46 in properly locating the burner with respect to said end wall.

Fastened, as by screws 47, to the forward end of the bracket 45 is a valve casing 50 having a bore 51 that is joined by a passageway 52 in a depending branch 53 of said casing. Connected by suitable joints to the lower end of the branch 53, and to a lateral branch 54 of the fuel conduit 20, are the opposite ends of a tube 55, the branch 54 of the conduit being extended through an opening 56 in the end panel 4. Fuel is delivered through

the tube 55 to the valve casing 50 when the valve 21 in the fuel conduit 20 is opened. Inwardly beyond its point of communication with the passageway 52, the bore 51 is reduced in diameter and threaded for cooperation with the threaded portion 58 of a valve stem 59 whose inner end is formed to effect a valve 59^a that is arranged to cooperate with a seat 60 surrounding the inner end of a further reduced portion 61 of the bore. Adapted to be secured by a union 62 to the threaded rear end 63 of the valve casing is the forward end of a tubular generator 64 that has a cap 65 applied to its end remote from said union 62, said cap having a relatively small orifice 67. Extending from the inner end of the stem 59, through the generator 64, is a rod 68 that is slightly less in diameter than the internal diameter of the generator and a fine wire 69 protrudes from the end of the rod 68 through the orifice 67. The threaded portion 68 of the stem 59 has a longitudinal groove 70, indicated by dotted lines in Fig. 6, through which fuel may pass from the enlarged portion of the bore 51 to the reduced inner end of the bore from which its escape is controlled by the valve 59^a.

Fitted about the stem 59 and occupying the outer counterbored end of the bore 51 is a packing gland comprised of an annulus 71, a body 72 of packing material, and a follower 73 that is urged inwardly by a cap 75 that is threaded on the outer end of the casing 50. The stem 59 is equipped with an operating handle 76. With the valve casing 50 secured as aforesaid to the bracket 45, the cap 65 of the generator is positioned within an opening in the wall 44 of the burner body, the generator being thus disposed across the slotted portion 36 of the burner and above the space between the end of the burner body and the deflector 38. To avoid undue outward movement of the stem 59, a stop 77 in the form of a split ring is contracted within a circumferential groove 78 that is formed adjacent the outer end of the threaded portion 58 of the stem and is designed for engagement with the annulus 71.

Assuming that the reservoir 19 is supplied with fuel and that air pressure prevails therein, the valve 21 may be opened to permit fuel to pass to the generator 22 and to the valve casing 50. A lighted match or other igniting means may now be held beneath the generator 64 of the starting burner and the valve of said starting burner opened by turning the handle 76 in a direction to retract the stem 59. This will allow the fuel to pass through the generator 64 in a thin film between the wall of said generator and the rod 68 and be vaporized, in which condition it will discharge through the orifice 67 into the goose neck portion 41 of the mixing chamber 40 where it will mix with air entering through the opening 43 and passage 42. The mixture will then

issue through the slots 36 and 37 and be ignited by the match or other lighter and burn about the generator 64 and about the adjacent end of the retort 22. Should the valve of the 5 starting burner be opened before the fuel is thoroughly vaporized and liquid fuel momentarily be discharged from the generator into the mixing chamber 40, it will flow down the inclined bottom wall of said chamber and 10 through the slot 37 where it will be ignited and the resulting flame will assist in heating the generator 64. The deflector 38 directs the flame of the liquid fuel or gas issuing from the slot 37 upwardly against the generator. 15 As soon as the retort 22 is heated sufficiently to vaporize the liquid fuel therein, its valve may be opened by means of the operating handle 23 thereby to discharge the vapor from said retort into the mixer 15 from where 20 it passes through the manifold 6 to the burner 10 and is ignited by the flame of the starting burner 30. The starting burner may now be turned off and the stove will continue to operate in the usual manner. 25 By constructing the burner of mating halves or sections that meet in a straight plane, the casting and the machining of the device are greatly facilitated and cheapened. After the sections are cast it is only necessary 30 to grind their engaging surfaces, saw or otherwise cut the slots 35, and bore the holes for the screws and dowel pin, the holes in the section 31 that receive the screws 33 and 47 being tapped or threaded. 35 Also, by virtue of this same feature, the burner may be very easily cleaned in case it becomes clogged from any cause, as by foreign matter, such as boiled over food, falling upon the burner and entering the slots 40 35. To clean the burner it is only necessary to remove the one screw 33 and withdraw the section 32 from the dowel pin 34, when all passages are readily accessible.

Having thus described my invention, what

45 I claim is:—

1. A starting burner comprising a hollow body having a wall provided with gas emitting openings that are confined to the upper portion of said body, a second wall rising 50 from one side of the first wall and provided with an aperture, and a third wall descending from the side of the first wall opposite the side from which the second wall rises, said third wall having a drain opening, the 55 interior of the body constituting a mixing chamber, and a generator extending across the first wall and having its discharge end engaged in the aperture of the second wall and a part remote from its discharge end 60 disposed above said drain opening.

2. A starting burner comprising a hollow body having a wall provided with gas emitting openings, a second wall rising from one side of the first wall and provided with an 65 aperture, and a third wall descending from

the side of the first wall opposite the side from which the second wall rises, said third wall having a drain opening, the interior of the body constituting a mixing chamber, a deflector opposed to said drain opening, 70 and a generator extending across the first wall and having its discharge end engaged in the aperture of the second wall.

3. In a burner of the character described, in combination with a support, a hollow body consisting of mating sections, each section having a peripheral wall that abuts the peripheral wall of the other section, means maintaining the sections in proper relation to each other and in correct position with 80 respect to the support, fastening means securing one section to the support, and further fastening means securing the sections together.

4. A starting burner comprising a hollow body having a wall provided with gas emitting slots extending transversely of the body, a second wall rising from one side of the first wall and provided with an aperture, and a third wall descending from the opposite side of the first wall, said body being comprised of mating sections that meet in a straight vertical plane extending longitudinally of the body and bisecting said slots and aperture, one of said sections in the 90 zone of the third wall having its mating surface depressed to provide an opening between the sections, a baffle opposed to said opening and formed of parts integral with the respective sections, a generator disposed 95 across the slotted wall and having its discharge end projected into the aperture of the second wall, and means holding the sections together.

In testimony whereof, I hereunto affix my 105 signature.

MARC RESEK.
